Primary Examiner — Katrina A Betton(74) Attorney, Agent, or Firm — Banner & Witcoff, Ltd.(57) CLAIM

The ornamental design for an interior of vehicle, as shown and described.

DESCRIPTION

FIG. 1 is a rear perspective view of an interior of vehicle showing our new design;

FIG. 2 is a front perspective view thereof;

FIG. 3 is a side view thereof; and,

FIG. 4 is a top view thereof.

The broken lines immediately adjacent to the shaded area represent unclaimed boundaries of the design. The broken lines showing the remainder of the interior of vehicle represent unclaimed subject matter and form no part of the claimed design.
